UNITED STATES PATENT OFFICE.

ARTHUR W. BERRESFORD, OF MILWAUKEE, WISCONSIN.

FREIGHT-CAR AND LOCK FOR FREIGHT-CAR DOORS.

1,210,264.

Specification of Letters Patent. Patented Dec. 26, 1916.

Application filed May 22, 1911. Serial No. 628,838.

To all whom it may concern.

Be it known that I, ARTHUR W. BERRESFORD, a citizen of the United States, residing at Milwaukee, in the county of Milwaukee and State of Wisconsin, have invented new and useful Improvements in Freight-Cars and Locks for Freight-Car Doors, of which the following is a full, clear, concise, and exact description, reference being had to the accompanying drawing, forming a part of this specification.

My invention relates to improvements in freight cars and locks for freight car doors.

The usual type of freight car is provided with doors which may be opened from the side or end of the car. A great deal of trouble has been experienced from unauthorized persons opening the car doors and damaging or stealing the freight. It is difficult, particularly in freight yards, to detect these persons as they stand between or behind the cars while they are opening the doors, and thus are hidden from view.

My invention aims to provide a freight car with means for locking the doors these means being adapted to be unlocked only from the top of the car. Accordingly in order to open the car it is necessary for a person to expose himself to view over the top of the car and hence unauthorized persons may be readily detected.

Other objects and advantages of my invention will hereinafter appear.

In the accompanying drawings I have illustrated several forms of my invention but of course it may assume various other forms and adaptations in practice. It should therefore be understood that my invention is not limited to the constructions chosen for purposes of illustration but is capable of being modified, embodied and applied in different ways.

The views of the drawings are as follows:—

Figure 1 shows a transverse sectional view of a car with the locking mechanism in side elevation. Fig. 2 shows a perspective view of the locking mechanism shown in Fig. 1. Fig. 3 shows a sectional view on line 3—3 of Fig. 1 with the operating parts in elevation. Fig. 4 shows a side elevation of a car with the locking mechanism in position in the same. Fig. 5 shows a perspective view of one form of key. Fig. 6 shows a perspective view of a modified form of

locking mechanism with part of the inclosing casing in section. Fig. 7 shows an elevation of a further modified form of locking mechanism in position on a car. Fig. 8 shows a sectional view on line 8—8 of Fig. 7. Fig. 9 shows a sectional view on line 9—9 of Fig. 7. Fig. 10 shows a sectional view of a car with a further modified form of locking mechanism in elevation. Fig. 11 shows a side elevation of a car with this form of locking mechanism in position in the same. Figs. 12 and 13 show detail views of parts of this form of locking mechanism. Fig. 14 shows a perspective view of a modified form of key.

The construction shown in Figs. 1 to 4 inclusive will be first considered. A spindle 1 provided with a worm or screw threaded portion 2 and a squared end 3 is journaled in bearing 4. It is arranged within the car and sufficiently below the roof to require a long key 5 to operate the same. The key is inserted through an opening in the car roof and engages the squared end of the spindle. The worm engages a pinion 6 mounted on a transverse shaft 7 journaled in suitable bearings. A finger 8 is preferably fixed to one end of the shaft 7 in any suitable manner and turns with a pinion to cast and retract a bolt 9 adapted to enter a suitable recess 10 in the car door. If desired a casing 11 may be placed around the worm and pinion and this casing may be provided with a suitable opening in its top to permit the movement of the bolt operating finger. In order to guide the key 5 a tube 12 may extend downward through the opening in the top of the car and have its lower end seated in the upper end of the casing 11. A pivoted cover 13 may be provided over the end of this tube and sealed if desired. A drain pipe or tube 14 having its upper end received by the casing 11 and its lower end extending through the bottom of the car and positioned in a collar 15 may be provided if desired.

When it is desired to unlock the door the person opening the same is required to have a long key adapted to extend down through the top of the car to the end of the spindle 1. On account of the size of this key an unauthorized person passing through the freight yard with such a key would be readily detected. In order to insert the key a person is further required to expose himself 110

to view on top of the car. When the key is rotated the rotary motion is conveyed from the spindle 1 and the pinion 6 to the finger 8 to cause this finger to move to and fro to 5 cast and retract the bolt 9 and thus lock or unlock the car door. It is obvious that due to the provision of the worm and pinion the person endeavoring to unlock the door would be required to expose himself for an 10 appreciable length of time and that the time required could be varied as desired.

In Fig. 6 I have illustrated another form which my invention may assume in practice. As in the previous construction I here employ 15 a vertical spindle preferably located in substantially the same position in the car and operable in the same manner. This spindle 16 is preferably journaled in suitable bearings in a box or casing 17 provided with suitable means arranged to fix it to the side of the car. A traveling nut 18 is arranged to move up and down upon the spindle 16 when the latter is rotated. This nut 18 is provided with a projection or 20 extension 19 which is adapted to enter a hole in a plate 20 carried on the side of the car door. The operation of this form of mechanism is substantially the same as that heretofore described, the nut traveling up and down the spindle as the latter is rotated and engaging or disengaging from the plate 20 to lock or unlock the car door.

In Figs. 7, 8 and 9 I have illustrated a 25 still further modified form which my invention may assume. As in the previous constructions this form of locking mechanism is operated by a thread spindle journaled in suitable bearings on the car side and rotatable in the same manner. This spindle 21 is arranged to mesh with a pinion 22 revolvably mounted upon a transversely extending spindle 23 having one end extending through the side of the car while the other end is of reduced diameter and is 30 arranged to reciprocate in a frame 24. A locking member 25 having serrated faces 26 engaging corresponding serrated faces on the pinion 22, is mounted upon the reduced portion of the spindle 23 and is normally held in engagement therewith by a spring 27. In suitable annular grooves in both the locking member 25 and the pinion 22 a helical spring 28 is housed which is of less 35 strength than the spring 27. The locking member 25 is thus resiliently held in engagement with the pinion and normally rotates with the same. When the spindle 23 is forced outward the serrated portion of the locking member 25 disengages from that of the pinion 22 so that the locking member or latch may be thrown to locking position by a suitable spring 29.

As in the previous construction this device may be inclosed in a suitable casing. 40 Also the operation is substantially the same

as that heretofore described. This device, however, is capable of being locked from the side of the car so that while the car door may be unlocked only from the top of the car it may be readily locked from the side 70 of the car.

In Figs. 10 to 14 I have illustrated a further modified form which my invention may assume. In these figures I have illustrated a vertical shaft 30 journaled in suitable 75 bearings 31 carried in the side of the car preferably at a point nearer the top than in the previous constructions. This shaft 30 carries a suitable latch 32 upon its lower end which latch is adapted to enter a suitable notch or recess 33 in the car door in order to lock the same. As in the previous construction the shaft 30 is provided with a squared end and is arranged to be rotated by a key which is inserted through the top 80 of the car. The key used in this construction, however, may have a shorter shank than the keys heretofore illustrated, as shown in Fig. 14. In order to automatically throw the spindle and the latch to locking 85 position I have provided a spring 34 encircling the shaft and having one end fixed at a point 35 to the shaft while the other end abuts against one of the bearings 31. As it is often desirable to provide some 90 means for holding the mechanism out of locking position so that the door will not snap locked automatically when closed I have provided a perforated plate 36 fixed to the upper end of the spindle 30 and arranged to rotate therewith. The perforations in this plate register successively with a perforation in a lug 37 preferably formed on one of the bearings 31 and a pin 38 may be dropped through these perforations to hold the locking mechanism in a retracted position. If desired the pin may be fixed to the end of a suitable chain 39 carried in 95 a convenient location near the plate 36.

By my improved construction I have provided a locking mechanism for freight car doors which may only be operated from the top of the car so that the person attempting to unlock the same is obliged to expose himself to view across the top of the car. Further a person in order to open the same is obliged to have a key of the proper type, preferably of a type which would render the person so conspicuous as to make him readily detected. Again the person is required to turn the key a number of times before the locking mechanism is opened and thus increase the time the person is exposed and thereby proportionately increase the chances of detection. On the other hand while the locking mechanism may only be unlocked from the top of the car this would not in any way interfere with its use by authorized persons since a single car or a string of cars could be unlocked on a single 100 105 110 115 120 125 130

5 trip over the top of the cars and the cars could later be locked from the side of the car without the necessity of another trip over the top of the car. Further, the construction is of a rugged type which is well adapted to withstand the rough usage to which such devices would be subjected in service and the mechanism is securely housed and protected within the car so that 10 it may not readily be tampered with by unauthorized persons. The mechanism is also of a type which may readily be applied to cars of standard construction without any material alteration of the cars.

15 While I have in this application described several forms in which my invention may be embodied these forms have however been used only as means of illustrating the principle of my invention and accordingly I do 20 not wish to be limited to these specific forms since it is obvious that my invention may assume various other forms and be widely modified.

25 What I claim as new and desire to secure by Letters Patent is as follows:—

30 1. In a lock for freight car doors, in combination, a latch, a releasing member for said latch operable only from the top of the car and a slow motion connection between said latch and said releasing member, said latch being operable to locking position from the side of the car.

35 2. A lock for freight car doors having in combination a latch, an operating member for releasing said latch, said member being accessible only from the top of the car, a motion reducing connection between the latch and said operating member to prolong the time required to withdraw said 40 latch, and means by which the latch may be quickly operated to locking position from the side of the car.

45 3. A freight car having a door and a locking mechanism therefor having a revoluble part requiring a number of turns to unlock the same and operable only from the top of the car, said locking mechanism having means permitting a quick locking of the door from the side of the car.

50 4. In a lock for freight car doors, in combination, a latch and operating means insuring a slow release thereof but permitting a quick operation of the same to locking position.

55 5. In a lock for freight car doors, a latch, a releasing member therefor accessible only from the top of the car, a slow motion connection between said releasing member and said latch and means on the side of the car 60 for disconnecting said latch from said releasing member to permit a quick operation of said latch to locking position.

65 6. In a lock for freight car doors, in combination, a latch, a releasing member therefor, accessible only from the top of the car,

a connection between said latch and said releasing member to insure a slow release of the former and means operable from the side of the car to disconnect said latch from said releasing member said latch when released from said member automatically locking the door when closed.

70 7. In a lock for freight car doors, a screw-threaded operating member, and a locking member arranged to be thrown to locking or unlocking position after a predetermined time, said member also having means permitting a quick locking of the door.

75 8. In combination, a latch for freight car doors, a revoluble releasing member therefor accessible only from the top of the car operative connections between said latch and said releasing member necessitating a plurality of complete revolutions of the latter to release the former, and means whereby said latch may be quickly thrown to locking position independently of said releasing means.

80 9. In combination, a latch for freight car doors, a revoluble operating member therefor accessible only from the top of the car an operative connection between said latch and said member including a worm and worm wheel, and means for operating said latch in one direction independently of said worm.

85 10. In a lock for freight car doors, an operating member, a rotating member arranged to be moved thereby, a locking member normally resiliently held in engagement with said rotating member and arranged to move therewith and means for throwing said locking member out of engagement with said operating member when desired.

90 11. In a lock for freight car doors, an operating member, a member arranged to move therewith, and a locking member arranged to move with said last mentioned member and means for disconnecting said last two members to throw the parts to locking position.

100 12. In a lock for freight car doors, a rotatable threaded operating member, a pinion arranged to engage therewith and be rotated by the same, a locking member normally arranged to move with said pinion and means for disconnecting said locking member from said pinion when desired to throw said locking member to locking position.

105 13. In a locking mechanism for freight car doors, an operating member arranged to be moved thereby, a locking member having a serrated surface normally in engagement with said rotating member, means for throwing said locking member out of engagement with said rotating member, and means operable independently of said disengaging means for actuating said locking member when thrown out of engagement with said rotating member.

14. A lock for freight car doors comprising a latch normally biased to locking position, operating means normally connected to said latch, said means being adapted to be actuated from the top of the freight car through an opening therein to withdraw the latch from locking position, and means operable from the side of the car for disconnecting the latch from the operating member to allow the latch to automatically return to locking position.

15. A lock for freight car doors comprising a latch normally biased to locking position, a rotatable member normally in engagement with said latch, an operating member adapted to be actuated from the top of the car through an opening therein for withdrawing the latch from locking position, and means operable from the side of the car for disengaging the latch from the rotatable member so that it may automatically

return to locking position independently of the operating member.

16. A lock for freight car doors comprising a pivoted latch normally biased to locking position, a rotatable worm gear having a serrated hub normally engaging a complementary hub on the latch, an operating worm shaft meshing with said gear, said shaft being arranged to be actuated from the top of the car through an opening therein, and means operable from the side of the car for disengaging the latch hub from the hub of the rotatable member so that the latch may be automatically moved to locking position.

In witness whereof, I have hereunto subscribed my name in the presence of two witnesses.

ARTHUR W. BERRESFORD.
